DISPLAY STAND

Olof Verner Anderson, North Kingston, R.I., assignor to Anson, Inc., Providence, R.I., a corporation of Rhode Island

Filed Jan. 1, 1967, Ser. No. 5,480

Term of patent 14 years

(Cl. D80—11)

FIGURE 4 is another perspective view thereof showing the lower shelf in an extended position;

This is a continuation-in-part of design application Ser. No. D.300, filed Dec. 23, 1965, now abandoned.

I claim:

The ornamental design for a display stand, as shown.
